Howard D. Smith INVENTOR.

BY
Edwin A. Smith ATTORNEY.

UNITED STATES PATENT OFFICE.

HOWARD D. SMITH, OF COLUMBUS, OHIO, ASSIGNOR TO THE NISLEY COMPANY, OF COLUMBUS, OHIO, A CORPORATION OF OHIO.

STORE FRONT.

Application filed December 26, 1924. Serial No. 758,266.

To all whom it may concern:

Be it known that I, HOWARD D. SMITH, a citizen of the United States of America, residing as Columbus, in the county of Franklin and State of Ohio, have invented certain new and useful Improvements in a Store Front, of which the following is a specification.

My invention relates to a store front and 10 is particularly concerned with the provision of an ornamental, unique and useful device for attracting the attention of persons by employing a novel arrangement of reflecting surfaces over a building entrance, which are 15 adapted to reflect light or the images of persons or objects on the street adjacent the building entrance to a remote point or to the opposite side of the street, where, by reason of each reflecting surface or mirror individually reflecting the images in converging paths, the illusive appearance of a large 20 number of objects or persons will be created.

The effectiveness of attention attracting 25 devices for advertising and similar purposes is well recognized, and a great variety of devices have been used or intended for this purpose. Prior devices, however, have usually depended upon ornamented display windows and the like to effect this object 30 and have required much labor, expense and time to maintain their attractiveness. The novelty of such devices is recognized as an important element in their effectiveness.

I have aimed at providing a device for the 35 purpose described, which consists generally in providing a plurality of reflecting surfaces or mirrors over or adjacent the building entrance which are arranged to reflect light or the images of persons or objects adjacent the building entrance to a remote point or to the remote side of the street in converging paths which will focus to produce the illusion of a large number of people 40 when in fact there may be only a few.

Another and further important element 45 in the novelty of this invention consists in the kaleidoscopic, multi-color or light effects obtained or produced when a series of differently colored objects pass in succession before the mirrors. This feature is adapted to secure and hold the attention of the observer by the fascinating color or light effects produced as objects or persons or lights pass in

front of the mirrors, but this will not interfere with the other effects produced and hereinafter described. At night the reflecting surfaces may be used to reflect light from the display windows or from any other source in practically the same manner as light or images are reflected in the daytime. 55 60

The principal object of this invention is to provide a device for the purpose described comprising reflecting surfaces or mirrors arranged over the building entrance in such a way as to attract the attention of persons at a distance or on the opposite side of the street by a multiple reflection of the images of persons or objects or light on the side of the street adjacent the building. The reflecting surfaces are arranged and intended to reflect the same number of images as there are reflecting surfaces over the building entrance, so that to an observer at a distance or on the opposite side of the street, one person or object will appear as several. 70 75 Furthermore, in the event of one or a few persons entering the building, it will appear to an observer on the opposite side of the street or at a distance, that a great many persons are entering the store, and will thus arouse curiosity and attention. 80

Another object of this invention is the provision of a device for the purpose described which will be effective to that end, attractive in appearance, simple in construction, and require little or no labor or expense to retain the novelty and attractiveness of the same. 85

A still further object of this invention consists in providing a store or building 90 front of any desired construction with my novel device incorporated as an integral part of the same to form a unitary, efficient, but at the same time removable addition to the design of the building. 95

Another and further object of my invention is the provision of a device for the purpose indicated which can readily be adapted to different requirements, and is flexible enough in principle to permit of many and varied adaptations of the same. 100

Various other objects of my invention will be apparent as this description progresses and will be brought out in the claims appended hereto. One embodiment of my invention is illustrated in the accompanying 105

drawings, wherein similar reference characters designate corresponding parts and wherein;

5 Figure 1 is a perspective view of my novel device as applied to a store or building entrance:

10 Figure 2 is a partial longitudinal vertical section through the center of the store or building entrance, shown in Figure 1, showing my novel arrangement of reflecting surfaces or mirrors over the entrance. The path of the incident and reflected light is also represented in this drawing by the arrows.

15 Figure 3 is a diagrammatic plan view of the mirror arrangement, which clearly shows the converging path of the light as reflected to a remote point or to the opposite side of the street by the mirrors over the building entrance. The lines representing the path of the light are not completely shown, but are shown sufficiently to make the purpose of the mirror arrangement easily understood.

20 In the drawings, with particular reference to Figures 1 and 2, my novel building front is shown as comprising the inset store or building entrance 1, on opposite sides and to the rear of which may be arranged the display windows 2 which are intended to display the merchant's goods to persons passing along the adjacent sidewalk. The doors 3 are provided for entrance to the store or building. It will be understood that the design or architectural construction of this store front forms no part of the present invention and the design shown and described is not intended as a limitation of use, but merely as illustrative of the application of my invention. It is also understood that the store or building front to which my invention is applied may be varied to suit available space, cost, and any number of other contingencies which may arise. My invention may also be adapted to existing conditions and is not necessarily confined in its application to the arrangement shown, and various other modifications and adaptations of the same are obvious and will appear to persons skilled in the art.

25 Above the store entrance and mounted upon the display windows 2, I have provided a plurality of mirrors or reflecting surfaces 4, which may be arranged in the manner shown in Figure 1 or in any other manner to which the existing space, building design, etc. may be better adapted. The mirrors or reflecting surfaces 4 may be secured in their respective positions with any suitable means, such as the strips 5 which are removable to permit replacement, repair or other changes. These mirrors 4 are arranged in a fan-like manner in general, or as about a semi-frustoconical surface. Because of the inclination of these mirrors and the general arcuate arrangement of the same, light or the image

of an individual or object reflected by the mirrors will converge downwardly and come to a focus at a predetermined position, which is preferably at a point remote from the store or building entrance.

70

In Figure 3 I have shown, in a somewhat diagrammatic way, the effect of this mirror arrangement in reflecting light or an image of an object or person adjacent the store entrance. This light or object or person is shown for convenience of illustration as at the point 6, and the rays of light are indicated by the dotted lines 7 as passing to and being reflected by the reflecting surfaces or mirrors 4 to a remote point. These mirrors are mounted so that light or the image of any object, such as a passing or stationary person or object, in front of the store or building entrance, will be reflected in a converging downwardly inclined path and focus to a remote point or to the opposite side of the street and there create the illusive appearance of a crowd of people. By my use of a plurality of mirrors of reflecting surfaces placed in angular proximity to one another, that is, with their reflecting surfaces disposed at a right or acute angle to one another, the image of one mirror becomes the object for the adjacent mirror and it in turn becomes the object for the other mirror and, therefore, to an observer, the image will be multiplied according to the number of successive reflections, which depends upon the angle between the reflecting surfaces and the position of the object.

80

90 In operation, light effects or the images of persons or objects on the side of the street adjacent the building entrance will be individually reflected by each mirror to a remote point or to the opposite side of the street, where, to an attending observer, it will have the illusive appearance or resemblance of a crowd of people entering the building or passing along the sidewalk in front of the store. The path taken by the incident and reflected light is shown by the arrows 7 in Figures 2 and 3 from which it will be obvious that the reflecting surfaces or mirrors may be inclined at such an angle 95 that the reflected light is inclined downwardly so that the effect of the device will appear to the best advantages on the side of the street remote from the store or building entrance.

100

110 In the installation of this device the same may be adapted to the existing conditions, and the foci and radii adjusted as to inclination and convergence, so that the desired effect may be produced regardless of street width or other conditions. It will be understood that the particular features of this invention may be varied, not only to adapt the device to different situations, but also to produce a variety of effects for different purposes. It might be desirable to provide con-

120

125

130

cave or convex faced mirrors to distort or otherwise modify the reflected image. This construction might be desirable where the device is employed over the entrance to a theater or amusement house. The mirrors might also be arranged along the vertical sides of the store front and the same result could be accomplished. The usefulness of this device might be enhanced by providing the name of the store or merchant on the mirror surfaces.

From the foregoing description, it will be obvious that I have provided a device of great advertising value, which is simple in construction, easily maintained, novel in appearance and function and adapted to perform in an efficient manner the aforementioned and other objects which will appear to persons skilled in the art.

Having described my invention, what I claim is:

1. In a store or building front, a plurality of reflecting surfaces disposed adjacent the top thereof, said reflecting surfaces being so arranged as to produce a plurality of images of an object within the focal range and to project said images to a point remote from said object.

2. A store front comprising an entrance and an arch, and reflecting surfaces carried by said arch, said reflecting surfaces being adapted to project a plurality of images of

an object within the range of said surfaces to a point remote from said store front.

3. In a store front, a front display section, an entrance way, and a plurality of reflecting surfaces arranged adjacent the top of said display section and said entrance way, said reflecting surfaces being disposed to multiply and project a plurality of images of an object to a point remote from said front.

4. In a store or building front, an inclined reflecting surface divided into sections, each section having individual reflecting properties, for producing a plurality of reflections from a single source and projecting said reflections to a point remote from the said source.

5. In a store front, a front section having an entrance way, and reflecting means arranged adjacent the top of said front section and entrance way, said reflecting means being comprised of a plurality of inclined reflectors defining separate surfaces.

6. In a store front, a plurality of reflecting surfaces disposed adjacent the top of said front in a fanlike manner, and adapted to reflect and project a plurality of images of an object within the range of the said reflecting surfaces.

In testimony whereof I affix my signature.

HOWARD D. SMITH.
